UNITED STATES PATENT OFFICE.

HUGH S. KERR, OF PHILADELPHIA, PENNSYLVANIA.

DESIGN FOR A TOY.

SPECIFICATION forming part of Design No. 25,310, dated March 31, 1896.

Application filed February 24, 1896. Serial No. 580,521. Term of patent 3½ years.

To all whom it may concern:

Be it known that I, HUGH S. KERR, a citizen of the United States, residing in Philadelphia, Pennsylvania, have invented a certain Design for a Toy, of which the following is a specification.

My design for a toy is fully illustrated in the accompanying drawing, the essential feature of the design being the star-shaped representation of a doll.

The design is represented as a five-point star. The upper point has on it the representation of a face with a cap above it. The center portion of the star represents the body, the two side members represent the arms of

the doll having hands printed on their extreme ends, and the two lower members of the star represent the limbs of the doll with representations of shoes at their ends.

I claim—

The design for a toy as fully described and illustrated in the accompanying drawing.

In testimony whereof I have signed my name to this specification in the presence of two subscribing witnesses.

HUGH S. KERR.
